UNITED STATES PATENT OFFICE

132,599

DESIGN FOR AN ACCORDION CASE

Walter Romanoff, Philadelphia, Pa.

Application March 14, 1942, Serial No. 106,200

Term of patent 14 years

To all whom it may concern:

Be it known that I, Walter Romanoff, a citizen of the Union of Soviet Socialist Republics, residing at Philadelphia, county of Philadelphia, and State of Pennsylvania, have invented a new, original, and ornamental Design for an Accordion Case, of which the following is a specification, reference being had to the accompanying drawing, forming a part thereof:

I claim:

The ornamental design for an accordion case, as shown.

WALTER ROMANOFF.
